UNITED STATES PATENT OFFICE

ETIENNE (KNOWN AS STEPHANE) JULIEN BRUN, OF LYON, FRANCE

APPARATUS FOR SELECTING LUMINOUS POINTS OF AN IMAGE FOR REPRODUCTION BY TELEVISION

Application filed March 24, 1927, Serial No. 177,989, and in France March 27, 1926.

The object of the present invention is to provide an apparatus for selecting the luminous points of an image and marking them in a much shorter time than that of previous devices and in great number so as to reproduce them at a distance in similar conditions.

The said apparatus essentially comprises two discs mounted on the same axis driven with a differential movement and formed with rectilinear slits which in one screen are arranged at an angle of substantially 45° to the radial slits in the other, in order to illuminate all the points of the image successively through the different intersections.

The invention also includes different dispositions whereby synchronism between the selection and the reproduction of the images, control, regulation and the transmission of colors, and vibratory movement suitable for transmission of electric waves may be obtained.

In the annexed drawing, Fig. 1 is an elevation of the apparatus facing the perforated discs;

Fig. 2 is a longitudinal section on the line A—A in Fig. 1.

Fig. 3 is a section on the line B—B in Fig. 1.

Fig. 4 is an outside view of a detail of the synchronising mechanism;

Fig. 5 is a front view of the current distributing plate;

Figs. 6, 7 and 8 represent the current regulator mechanism in elevation, profile and plan; and

Fig. 9 is a diagram of the different electric controls of the apparatus.

The apparatus comprises two frames 1, which are connected by cross members 2 and in which are mounted shafts 3, 4 and 5, driven at different speeds by toothed gears and pinions 9 and 10. On the shaft 4 is mounted one of the screens 6 while an external tube 7 concentrically arranged over shaft 4 carries another screen 8.

A small shaft 11 arranged at right angles to the above mentioned shafts, is driven by the shaft 5 through a worm 12.

The two discs 6 and 8 have on their peripheries, the one radiating slits and the other an equal number of slits, inclined at about 45° with respect thereto. The discs rotate at high speed with a predetermined difference, so that they are found periodically in the same respective position. The period, in which all the luminous points are explored, constitutes an image.

The luminous rays passing through the intersection of the slits in the discs are passed through an opaque screen 5'. This screen is placed between the subject and the transmitting apparatus as close as possible to the discs.

The object of the opaque screen is to interrupt the luminous rays before they reach the photo-electric cell generally used in devices of this character. These interruptions will, acting on the photo-electric cell, produce a vibratory current which, amplified, will be transmitted by the transmitting station to the receiving station.

In order to permit the transmission of colors, the slits in one of the discs may have colored screens giving alternately the three complementary colors of the spectrum that is, red, yellow and blue screens so as to reproduce the same colors when receiving as when transmitting by means of a similar device. The duration of impression on the retina, permitting the mixing of the colors, gives the actual impression of the shades to be reproduced.

Television, which can be transmitted by wire or by electric waves, is obtained with two similar apparatus, one arranged for transmitting and the other for reception. The apparatus should turn exactly at the same speed.

In order to obtain synchronism, the apparatus comprises a local horal control and means for producing an automatic regulation of the speed of the driving motor M and of the agreement of the periods constituting the image.

The present invention relies upon local synchronism obtained by two clocks regulated as exactly as possible on the astronomical hour.

The local horal control is provided by a clock 22, installed at each post with a second mechanism beating the astronomical second and sending an electric signal at each second. On each apparatus counter mechanism 5 also sends a signal to an electric minute mechanism provided with a second mechanism 28 arranged in proximity to the clock, in order to facilitate comparison of the working of the clock and of the minute mechanism, which ought to be the same, each second comprising the number of images adopted.

10 The speed and periodic concordance regulator comprise an initial hand control 15 through a starting rheostat. The electric current thus flows through a starting resistance of variable degree controllable at will.

20 A centrifugal force regulator adjustable by hand, replaces the starting rheostat for the motor when the desired speed is attained. The speed of the two apparatus (transmitting and receiving) being equal, it is 25 possible for the periods constituting the image to overlap and the regularization i. e., the synchronism as distinct from isochronism is completed by the mechanism to be herein-after referred to.

30 In operation the apparatus is driven by an electric motor M preferably of the universal type, actuating the driving shaft 3 on which is mounted the gears 9 and 10. These gears 9 and 10 rotate the discs 6 and 8 35 through shafts 4 and 7 respectively, and are timed to drive the discs at a slight difference of speed with respect to each other permitting all the luminous points of an image to properly pass through the cooperating slits formed in discs 6 and 8.

40 By regulating the relative speed of the discs it will be understood that the size of the slits will be varied whereby the best illumination and distinctiveness may be obtained.

45 Synchronism between the selection and the reproduction of the images is obtained by the two following successive regulations:

1. The regulation of the speed of the 50 motor as approximately as possible by means of a hand controlled variable resistance 30, and such hand control can be replaced by automatic control during a long interval by means of a centrifugal force regulator 13 55 mounted on the regulating shaft 5, the regulator 13 having for its object to fix the speed of the motor to one slightly higher than that required for synchronism and,

60 2. The regulation of the speed determining perfect synchronism between two similar positions of the transmitting and receiving apparatus, by means of a disc 14, keyed to and driven by the shaft 5. This disc 14 is provided on its circumference with a tooth 65 or projection 15 (Fig. 6) meeting a flexible

spring 16 so as to produce an efficient light 70 braking resistance of the apparatus at the desired point. The spring produces only a momentary torque upon 14 and not a complete arrest. This flexible spring 16 is locked at its extremity in a movable mounting 17 arranged to damp the vibrations of the spring at the moment at which it leaves the cam 15, allowing however the said spring 75 to rise in the event of erroneous rotation in the opposite direction. The braking point may be modified by an arrangement, to be hereafter referred to, turnable on the shaft 5 so as to harmonize the starting point of the formation of the image on the transmitting apparatus and the receiving apparatus. The cam is retarded at every turn of the shaft 5 by the spring 16, except when the solenoid 21 comes into operation and displaces it.

80 The flexible spring 16 can be moved from its normal position in order to escape the tooth 15, by means of the members 17, 18, 19 and 20 and an electro-magnet or solenoid 21 (Fig. 7) receiving the electric signals 85 from the local or regulating clock 22 through the commutator 23.

The solenoid circuit is as follows:—

With reference to Fig. 9 it will be seen 90 that the clock is connected to two terminals 22^a and 22^b. Terminal 22^a is connected to one terminal of the solenoid and 22^b is connected to one terminal of the commutator 23, the other terminal of the commutator 23 95 being connected to the other terminal of the solenoid 21. Expressed differently, solenoid 21, clock 22 and commutator 23, are arranged in series.

100 Support 18 is provided with an opening 105 for passage of spindle 19. Spindle 19 can move horizontally, in the support 18 around screw 19^a (upon operation of the lever 20), which screw holds a spring 19^b bearing on a plate 19^c which plate together with spring 16 is capable of upward movement in the event of erroneous rotation of 14 in an anti-clockwise direction.

110 The solenoid 21, under the action of the electric current sent by the seconds-beating regulating clock, after its passage through 115 the commutator 23 moves lever 20 and produces horizontal deviation of the mounting 17 and so brings about the escape of the flexible spring from the cam or tooth 15. Any suitable means may be employed for connecting lever 20 to spring 16. This movement 120 will take place when the one of the two carbon brushes 24 which is placed furthest from the centre of the commutator 23 (see Fig. 3) meets the exterior metal part of the disc 23.

125 The commutator 23 comprises a disc of insulating material mounted at the end of shaft 5 (see Fig. 3) and making one turn per image. The shaft 5 which carries the 130

centrifugal force regulator as well as cam 14 and the disc 23 takes its movement from the motor shaft 3 in the ratio 1 to 4. The gear ratios and motor speeds heretofore given enable it to be established that shaft 5 makes 1 turn per image, since shaft 5 makes about 12 turns per second and discs 6 and 8 are arranged to make 12 turns per image by suitable gearing with the motor shaft.

On the disc 23 (see Fig. 5) is placed a thin metal piece 23^a of which the central part is in constant contact with one of the carbon brushes of the commutator, whilst extension 23^b gives contact with the other carbon brush. The said two brushes are contained in a block of insulating material and are pressed by two small spiral springs receiving current from two rings to which the electric current is brought by two leaf springs. This block is mounted on a shaft co-axial with shaft 5 and to prevent it from being turned due to contact of the brushes with the commutator it is braked by means of two steel leaves between which, however, it may be turned by hand.

The speed of rotation of the discs being regulated elsewhere by the arrangements previously described, this block will have for its object to cause the apparatus to be braked each time the tooth 15 does not pass at the desired moment in front of the spring 16.

To establish the contact to operate the solenoid 21 and obtain a perfect synchronism the electrical clock 22 which beats seconds, sends at each second current from a battery 31 to the rotary switch or commutator 23 placed at the extremity of the shaft 5, lever 20 permitting solenoid 21 to bring the spring out of the path of the tooth 15 if the clock 22—solenoid 21—commutator 23 circuit is made at the required moment. The two carbon brushes 24 in contact with disc 23 make circuit for the current sent by the clock 22 when the two contacts fall on the metallic part. The current is, on the other hand, interrupted, when one of the brushes 24 is in contact with the insulating part.

To ensure regulation of the receiving apparatus in synchronism with the transmitting apparatus, the commutator 23 (which is capable of varying the point where the signal should cease to act) is held so that the operator at the receiving station may rotate it by hand and so vary the point of braking until the image becomes correctly centered, the instants corresponding to the beginning of the period constituting the image, then being in harmony on the transmitting and receiving apparatus.

The transmitting post having similar apparatus to that at the receiving post each clock sends to the apparatus an electric signal at each second. The two apparatus being arranged to produce, say, twelve im-

ages per second the arrangement actuated by the electric signal from the clock will brake the movement so as to bring about harmony.

The operator at the transmitting post does not vary the moment of braking of the transmitting apparatus this being done only at the receiving station.

The displacement of the flexible spring 16 only takes place when the clock signal corresponds to the position of the commutator. The operator at the receiving station can thus, by feeling his way, find out the position of the commutator which is most favorable to the formation of a distinct image on the receiving screen.

On the counting shaft 11 driven by the worm 12 at a speed of one revolution per second, is mounted a disc 25 graduated in fractions of seconds to allow the operator to appreciate differences of speed of the apparatus by checking with the local clock, which clock is regulated as exactly as possible on the astronomical second.

Shaft 11 rotates at one revolution per second in accordance with the aforesaid gear ratios of shafts 3 and 5 and with the motor speed adopted. A suggested range for motor speeds was given as 2500 to 3000 R. P. M.

Interaction of the cam 26 and lever 27 cause to be sent, at each turn of shaft 11, that is at each second (since shaft 11 rotates at 1 revolution per second) current from a battery 32 to a minute mechanism 28. With reference to Fig. 9 it will be seen that mechanism 28 having an hour-minute-second dial similar to clock 22 and battery 32 are connected to the two terminals adjacent the terminals 22^a and 22^b. The two former terminals are connected to the switch member 33 (see Fig. 4) contact between 34 and 35 effecting the sending of current through the mechanism 28, 34 and 35 come into contact due to depression of the beak 36 caused by the said interaction of the cam 26 and the lever 27. The two said terminals are connected, the one, to 34 and, the other, to 35.

The minute mechanism 28 and the dial 25 (graduated in fractions of seconds) count the number of revolutions made by the shaft 11, shaft 11 rotating once per second. If shaft 11 does not, by error, rotate once per second this will be shown by comparison of the clock 22 with the mechanism 28 and dial 25.

Mechanism 28 being capable of adjustment with regard to the time of the clock or regulator 22, the difference of speed of the apparatus with that at which it must normally turn can be observed at each instant by comparison of the two dials. The dial of this minute mechanism (placed close to the clock and within reach of the op-

erator's hand) can easily be set right again, in order to allow a very exact checking of the speed of the apparatus. The minute mechanism 28 has for its object to check the synchronism of the apparatus.

6 The reproduction of colors is obtained directly by using red, yellow and blue screens arranged on one of the discs preferably on the face adjacent the remaining disc and covering the slits in the disc carrying said colored screens.

10 It is to be understood that the apparatus shown and described is capable of many modifications and those modifications that are within the scope of the claims, I consider within the spirit of the invention.

I claim:

1. An apparatus of the character described comprising a driving shaft, gears carried by said shaft, a pair of discs each rotated in the same direction by the said gears and adapted to be driven at a different speed with respect to each other, one of said discs having radial slits and the others having slits formed at an angle substantially 45 degrees with respect to the slits of the first mentioned disc.

20 2. An apparatus of the character described comprising a pair of discs rotating concentrically in the same direction and with a differential movement, said discs having slits formed therein, the slits in one disc being formed at different angles to the slits in the remaining disc, and the slits of both discs being arranged in rectilinear relation.

25 3. An apparatus of the character described comprising a pair of discs rotated concentrically in the same direction and with a differential movement, one of said discs having radial slits formed therein and the other having slits inclined at substantially 45 degrees with respect to the first mentioned slits, said radial and inclined slits of the respective discs being arranged in rectilinear relation.

40 4. An apparatus of the character described comprising a pair of discs rotated concentrically in the same direction and with differential movement, one of said discs having radial slits formed therein and the other having slits inclined at substantially 45 degrees with respect to the first mentioned slits and series of red, yellow and blue screens secured to one of said discs and covering the slits of the latter whereby to obtain a reproduction of colors.

45 5. An apparatus for selecting luminous points of an image for reproduction by television comprising a pair of discs rotated concentrically in the same direction and with a differential movement, said discs having slits formed therein, the slits in one disc being formed at a different angle to the slits in the

remaining disc, the slits of both discs being arranged in rectilinear relation, and an opaque screen interposed between the image to be reproduced and the discs for the purpose specified.

6. An apparatus for selecting luminous points of an image for reproduction by television, comprising a pair of discs mounted to rotate concentrically in the same direction and with a differential movement, one of said discs having radial slits formed therein and the other having slits inclined at substantially 45 degrees with respect to the first mentioned slits, said radial and inclined slits of the respective discs being arranged in rectilinear relation, a motor for driving said discs, a double action centrifugal regulator controlling the speed of said motor, means for braking the motor at a precise point, a clock regulated on the astronomical hour for determining the movement of action of said motor braking means and adjustable means for varying the moment of action of said braking means whereby to harmonize the starting point of the formation of the image on the transmitting and receiving apparatus.

7. An apparatus for selecting luminous points of an image for reproduction by television, comprising a pair of discs mounted to rotate concentrically in the same direction and with a differential movement, one of said discs having radial slits formed therein and the other having slits inclined at substantially 45 degrees with respect to the first mentioned slits, said radial and inclined slits of the respective discs being arranged in rectilinear relation, a motor for driving said discs, a double action centrifugal regulator controlling the speed of said motor, means for braking the motor at a precise point, a clock regulated on the astronomical hour for determining the movement of action of said motor braking means and a dial indicator for the speed of the apparatus graduated in time unit and allowing of comparison with said clock.

8. An apparatus for selecting the luminous points of an image for reproduction by television comprising a motor for driving said apparatus, a double action centrifugal regulator controlling the speed of said motor, means for braking the motor at a precise point, a clock regulated on the astronomical hour for determining the movement of action of said motor braking means, and adjustable means for varying the movement of action of said braking means whereby to harmonize the starting point of the formation of the image on the transmitting and receiving apparatus.

In witness whereof I have hereunto set my hand.

ETIENNE (d: STEPHANE) JULIEN BRUN.
